UNITED STATES PATENT OFFICE.

HENRY F. RATHJEN, OF PEORIA, ILLINOIS.

MASON'S JOINTER.

Application filed July 22, 1927. Serial No. 207,722.

This invention relates to a jointer for use in brick construction work.

An object of the invention is to provide a jointer whose parts may be separated whereby the member that is applied directly to the work may be replaced by another of different form.

Another object is the provision of a jointer whose parts are adapted to be loosened whereby the member that is applied directly to the work may be changed in position to provide a new working surface.

Still another object is to furnish a jointer for mason's use that will provide for interchanging the actual working member, or admit of its change in position for presenting a different working surface thereon and yet so constructed that the various parts will be thoroughly rigid relatively.

To the end that the invention may be fully understood the accompanying drawing is provided wherein:

Figure 1 is a side elevation of one form of the jointer of my invention.

Figure 2 is a side elevation of another form of the invention.

Figure 3 is a transverse section of the tool produced on line 3-3 in both Figures 1 and 2.

Figure 4 is an end elevation of the form of tool shown in Figure 1.

Figures 5 and 6 are end elevations of two forms of a working member usable with either type of device shown, and

Figure 7 shows in perspective a part of a holding portion of my improved jointer.

In Figure 1 the numeral 1 designates that portion or member of the tool that is directly applied to the work. As shown in said figure, and in Figure 5 which shows the full size, the member is of square form, as is also true of the form of tool shown in Figure 2, while in Figure 6 it is shown of round form, or it may be any other form desired.

A handle structure is shown in said Figure 1 which in the present instance comprises three parts, a grasping piece 2, and two holding portions 3, 4, these latter portions being secured each at one of its ends to the grasping piece 2 by a screw 5 passing through all three holding them in rigid relation.

The holding portions 3 and 4 extend away from the ends of the handle 2 and at their

free ends engage the ends of the member 1, said holding portions being suitably formed to space said handle a desired distance from said member. The end of the portion 3 has a terminal end 6 to overlie the end of the member 1 and includes a fin 7, for example, on its inner surface adapted to lie in either of two grooves 8 of said member, said fin having an extension 6' to enter a central cavity 7' in the end of the member, Figures 5 and 6, by which the member is maintained in a fixed position relative to the handle.

The end of the portion 4 remote from the handle 2 has a terminal end 9 similar to the end 6 and includes a boss 10 substantially paralleling the axis of the handle 2 and lies in a socket 11 in said member 1. Both portions 3 and 4 may be provided with lugs 12 to overlie the member 1 constituting a saddle to receive the said member into it as in Figure 3.

As stated earlier herein my object is to substitute one form of the member 1 for another as well as to enable the workman to present different working surfaces of a member to the work. By loosening the screw 5 the portions 3 and 4 may be separated sufficiently to permit the fin 7 to draw out of the groove 8 in which it lies thus permitting the member 1 to be removed and replaced by another or to be rotated to any desired position whereupon the screw upon being tightened secured the parts relatively rigid. It is clear in this connection that one of the portions 3, 4 may, if desired, be a part of the handle 2 so that by a sufficient loosening of the said screw the other will have enough end movement to accomplish the end stated.

The form in Figure 2 is adapted for use in working in narrow or confined spaces. It includes the member 1' of any of the forms mentioned and the handle 2' has attached thereto or formed therewith a holding portion 3' having saddle portions 12', if desired, and the terminal end 6' including the fin 7' to lie in the groove in the end of the member 1' as in the first instance, a screw 8' extending through the end 6' into the member serving to complete the assembly.

It is to be understood that it is not my purpose to confine myself to the exact mode of securing the members 1, 1' from rotating or holding the same in place in the handle structure since other methods are open for

use, I having described and shown but one efficient form for so doing.

I claim:

1. In a mason's jointer, a handle, a member for application to the work, a portion extending from each end of said handle, each engaging an end of the member positively supporting the same therebetween, one of the portions and the member having a portion complementary to one another adapted to engage for preventing the member rotating, and means to secure the handle and said portions relatively rigid and for clamping the member between said portions.
- 15 2. A mason's jointer including a handle, a holding portion extending from end thereof rigid therewith, and a part of which portion is disposed substantially parallel to the handle's length including a saddle, a work engaging member adapted to engage the saddle, the said holding portion arranged to engage upon one end of the member, and means to secure the member and portion relatively.
- 20 3. A mason's jointer including a handle, a holding portion extending from one end thereof rigid therewith, a part of which portion is disposed substantially parallel to the handle's length including a saddle in one side thereof, a work engaging member adapted to be lodged in the saddle, said holding portion arranged to engage upon an end of the member and having a fin extending from its surface, said member having a groove in its end to receive said fin, and means to secure the member and portion relatively.
- 25 4. A mason's jointer including a handle, a holding portion extending from each end

of the handle, a part of one of which is disposed substantially parallel to the handle's length and having a saddle, a work engaging member adapted to be lodged in the saddle, each of said holding portions arranged to engage an end of the handle, and one of them having a fin extending therefrom, said work engaging member having a groove in one end to receive said fin, and means to secure the handle, said holding portions, and the member relatively rigid.

40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

5. A mason's jointer including a handle, a holding portion abutting upon each end of said handle a part of each of which substantially parallels the handle's length and including a saddle, and each also including a terminal and disposed substantially at right angles to the said handle's length, a work engaging member interposed between the terminals and held thereby and having a groove in one end, and also adapted to be lodged in the saddles of the said holding portions, a fin on one of the terminals to engage in the said groove in the end of the member, and means to secure the handle, the portions and the member relatively.

6. A mason's jointer including a handle, a holding portion abutting upon one end of the same and affixed thereto, a work engaging member having groove across an end thereof, said holding portion having a terminal end to receive the end of the member against it and including at that end a fin to engage in said groove, and means to secure the handle, said member, and the holding portion relatively rigid.

In testimony whereof I affix my signature.

HENRY F. RATHJEN.
